UNITED STATES PATENT OFFICE

2,597,688

PORTABLE TRAILER MIXER

Chauncey D. Vought, Greenville, S. C.

Application March 16, 1950, Serial No. 150,007

10 Claims. (Cl. 259—178)

1.

This invention relates to apparatus for use in mixing cement, mortar and the like and, particularly, apparatus of this type and kind which can be conveniently moved to a place of use as a trailer and, while on the job, can be conveniently positioned to minimize handling or transportation of the mixture, so as to expedite the use of the mixed materials and, thus, effecting a saving of time. More particularly, the invention deals with a mixing apparatus, wherein the mixer or agitator is bodily movable into and out of a mixing trough arranged upon a supporting surface, so as to facilitate pick-up and conveyance of the trough with the mixture therein to a point of use, while mixing another batch in a second or third trough.

The novel features of the invention will be best understood from the following descriptions, when taken together with the accompanying drawing, in which certain embodiments of the invention are disclosed and, in which, the separate parts are designated by suitable reference characters in each of the views and, in which:

Fig. 1 is a perspective view of an apparatus made according to my invention showing the mixer blade in a partially raised position with respect to a trough.

Fig. 2 is a side and sectional view of the apparatus showing the mixing blade in lowered operating position in a trough.

Fig. 3 is a sectional plan view of the structure, as seen in Fig. 2, omitting parts of the construction.

Fig. 4 is an enlarged sectional view on the line 4—4 of Fig. 1; and

Fig. 5 is a side view of a trough lifting and conveying device which I employ with part of the construction broken away.

In the drawing, I have shown at 10 the chassis or frame of the trailer mixer, on the rear portion of which is arranged a box-shaped housing or casing 11 and, at 12, are shown spring supports for an axle 13, on which the trailer wheels 14 are mounted. The top of the casing 11 has hinge covers 15 to give access to said casing. The front wall of the casing has apertures 16 at the sides thereof, through which part of a drive is passed, as later described.

Supported at the forward end of the chassis or frame 10 are two vertical frame members 17. Each frame member is of the same construction, so that the brief description of one will apply to both. These frame members comprise two pairs of rails 18 and 19 coupled together at longitudinally spaced intervals by a bottom

cross-plate 20 and part of the frame, as at 21, note Fig. 1.

Disposed between the pairs of rails, adjacent the outer edges thereof, are longitudinally spaced rollers 22 which form between the rails channels 23, in which plates 24 are slidably mounted. Each plate 24 has a bearing portion, for an agitator blade shaft 25, on which shaft is secured an agitator blade unit, as at 26. The unit 26 includes 10 curved segments 27 of a circle which are adapted to be brought into close proximity to the contour of the trough 28, in which the mixture is to be prepared.

On the shaft 25, adjacent the frame 17, are secured sprockets 29, around which pass drive chains 30, which also pass around other sprockets 31 on a supplemental drive shaft 32.

Pivoted to each side of the housing 11, as at 33, are operating levers 34 having counter-balance weights 35 at their rear ends. These levers are pivoted to the plates 24, as at 36, and also include forwardly extending hand-grip portions 37. By this construction, the blade unit 26 may be moved into raised and lowered positions with respect to the mixing trough 28. Movable with the agitator unit 26 is a shield housing, comprising side plates 38 and a back plate 39, the housing being coupled with the slide plates 24, as at 40.

30 Supported on the bottom plate 41 of the chassis, within the housing 11, is a suitable drive motor or engine as at 42, which, in the construction shown, is in the form of a small gas engine. It will be understood, however, that any type of power can be utilized. The engine or motor 42 operates a main drive shaft 43 supported in suitable bearings as at 44, between which bearings is a clutch 45 controlled by a lever 46. On the shaft 43 is a pinion 47 for actuating a gear 48 on an idler shaft 49. On the shaft 49 is a pinion 50 which meshes with a gear 51 on a supplemental drive shaft 32, thus producing the drive to the drive chains 30 for actuating the blade unit 26, as will be apparent. The trough 28 is supported on spaced leg members 52 which maintains the bottom of the trough above a supporting surface for engagement by a wheeling or conveying unit 53 which is shown in Fig. 5.

It will also appear that the side walls of the trough 28 have, at their upper edges, slots 54 for reception of the shaft 25 so that the mixer unit 26 is embedded in the trough or has its axis at a point below the upper edge of the trough.

After a batch of concrete, mortar or the like 55 has been mixed, the agitator 26 is moved into

raised position and, then, the unit 53 is moved beneath the trough to lift the same and then conveyed to a point of delivery. The unit 53 comprises a pair of side rails, one of which is seen at 55 in Fig. 5 of the drawing, braced by cross-straps, as at 56. Pivoted to the lower ends of the rails 55 are rubber-tired wheels, one of which is seen at 57. It will be understood that the lower portions of the rails 55 are spread-apart a distance greater than the width of the trough 28 to dispose the wheels 57 beyond the limits of the side walls of the trough. Supported between the rails 55, as at 58, are a pair of curved fingers 59, which are adapted to slip beneath the trough and form supports for maintaining the trough in substantially horizontal position in conveyance of the trough to a position for use.

On the side rails 55 are V-shaped leg members 60, which in conjunction with the wheels 57, will maintain the trough in position while the contents are being consumed. It will thus be apparent that several troughs can be utilized on a job and conveyed to a position for use, at which position, the troughs may be lowered to be supported on their feet 52. On the other hand, in other uses, the trough can be left in the unit 53 until the contents is removed and then wheeled back for the mixing of a new supply.

Units of the type and kind under consideration can be practically used on a fairly large job serving several men and, at the same time, can be very practically used in a small job where one or two men are performing the desired operations. By reason of the construction of the apparatus, the same can be produced economically and can be conveniently transported from place to place as a trailer, suitable means being provided to couple the same with a car or truck.

Having fully described my invention, what I claim as new and desire to secure by Letters Patent is:

1. A portable mixing apparatus of the character described, comprising a chassis, a housing on the chassis, a pair of vertical frame members on the chassis in spaced relation to said housing, plates slidably engaging said frame members, said plates supporting a shaft on which is disposed agitator blades, said plates, shaft and blades forming an agitator unit movable vertically in said frame members, drive means arranged in said housing, means comprising a pair of chain drives actuated by said drive means for operating the agitator unit, while permitting vertical swinging movement of the unit in said frame members, and a pair of levers pivoted to the housing and to said plates for moving the agitator unit into raised and lowered positions in the chassis.

2. A portable mixing apparatus of the character described, comprising a chassis, a housing on the chassis, a pair of vertical frame members on the chassis in spaced relation to said housing, plates slidably engaging said frame members, said plates supporting a shaft on which is disposed agitator blades, said plates, shaft and blades forming an agitator unit movable vertically in said frame members, drive means arranged in said housing, means comprising a pair of chain drives actuated by said drive means for operating the agitator unit, while permitting vertical swinging movement of the unit in said frame members, a pair of levers pivoted to the housing and to said plates for moving the agitator unit into raised and lowered positions in the

chassis, and means on said levers for counter-balancing said units.

3. A portable mixing apparatus of the character described, comprising a chassis, a housing on the chassis, a pair of vertical frame members on the chassis in spaced relation to said housing, plates slidably engaging said frame members, said plates supporting a shaft on which is disposed agitator blades, said plates, shaft and blades forming an agitator unit movable vertically in said frame members, drive means arranged in said housing, means comprising a pair of chain drives actuated by said drive means for operating the agitator unit, while permitting vertical swinging movement of the unit in said frame members, a pair of levers pivoted to the housing and to said plates for moving the agitator unit into raised and lowered positions in the chassis, means on said levers for counter-balancing said units, the drive between said drive means and chains comprising main and supplemental shafts and a gearing for transmitting movement of one shaft to the other shaft, and a manually operated clutch on the main shaft.

4. A portable mixing apparatus of the character described, comprising a chassis, a housing on the chassis, a pair of vertical frame members on the chassis in spaced relation to said housing, plates slidably engaging said frame members, said plates supporting a shaft on which is disposed agitator blades, said plates, shaft and blades forming an agitator unit movable vertically in said frame members, drive means arranged in said housing, means comprising a pair of chain drives actuated by said drive means for operating the agitator unit, while permitting vertical swinging movement of the unit in said frame members, a pair of levers pivoted to the housing and to said plates for moving the agitator unit into raised and lowered positions in the chassis, a mixing trough adapted to be positioned beneath the agitator unit and in which blades of the unit are adapted to operate in the use of the device, and said trough having supporting leg members spacing the same above a surface on which the apparatus is arranged.

5. A portable mixing apparatus of the character described, comprising a chassis, a housing on the chassis, a pair of vertical frame members on the chassis in spaced relation to said housing, plates slidably engaging said frame members, said plates supporting a shaft on which is disposed agitator blades, said plates, shaft and blades forming an agitator unit movable vertically in said frame members, drive means arranged in said housing, means comprising a pair of chain drives actuated by said drive means for operating the agitator unit, while permitting vertical swinging movement of the unit in said frame members, a pair of levers pivoted to the housing and to said plates for moving the agitator unit into raised and lowered positions in the chassis, a mixing trough adapted to be positioned beneath the agitator unit and in which blades of the unit are adapted to operate in the use of the device, said trough having supporting leg members spacing the same above a surface on which the apparatus is arranged, and a housing on said unit enclosing side and back portions of the trough.

6. A portable mixing apparatus of the character described, comprising a chassis, a housing on the chassis, a pair of vertical frame members on the chassis in spaced relation to said housing, plates slidably engaging said frame members, said plates supporting a shaft and blades form-

ing an agitator unit movable vertically in said frame members, drive means arranged in said housing, means comprising a pair of chain drives actuated by said drive means for operating the agitator unit, while permitting vertical swinging movement of the unit in said frame members, a pair of levers pivoted to the housing and to said plates for moving the agitator unit into raised and lowered positions in the chassis, a mixing trough adapted to be positioned beneath the agitator unit and in which blades of the unit are adapted to operate in the use of the device, said trough having supporting leg members spacing the same above a surface on which the apparatus is arranged, a housing on said unit enclosing side and back portions of the trough, and said housing being coupled with and movable with said plates.

7. A mixing apparatus of the character described, comprising a trailer having a frame, means comprising wheels for supporting the rear end portion of the frame, a housing arranged upon the rear end of the frame, means forming vertically arranged channels at the other forward end of the frame, an agitator unit slidably engaging the channel forming means for moving said unit into and out of a mixing trough disposed beneath and in alinement with said channel forming means, a motor in said housing operating a main drive shaft, and means including a supplemental drive shaft in operative connection with the main drive shaft for actuating said agitator unit.

8. A mixing apparatus of the character described, comprising a trailer having a frame, means comprising wheels for supporting the rear end portion of the frame, a housing arranged upon the rear end of the frame, means forming vertically arranged channels at the other forward end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, and means for moving the agitator unit into raised and lowered positions.

9. A mixing apparatus of the character de-

scribed, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith.

10. A mixing apparatus of the character described, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith.

15. A mixing apparatus of the character described, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith.

30. A mixing apparatus of the character described, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith, and a manually actuated clutch controlling drive between the main and the supplemental shafts.

35. A mixing apparatus of the character described, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith, and a manually actuated clutch controlling drive between the main and the supplemental shafts.

40. A mixing apparatus of the character described, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith, and a manually actuated clutch controlling drive between the main and the supplemental shafts.

45. A mixing apparatus of the character described, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith, and a manually actuated clutch controlling drive between the main and the supplemental shafts.

50. A mixing apparatus of the character described, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith, and a manually actuated clutch controlling drive between the main and the supplemental shafts.

55. A mixing apparatus of the character described, comprising a trailer having a frame, a housing at one end of the frame, means forming vertically arranged channels at the other end of the frame, an agitator unit slidably engaging the channel forming means for moving said unit into and out of a mixing trough disposed beneath and in alinement with said channel forming means, a motor in said housing operating a main drive shaft, means including a supplemental drive shaft in operative connection with the main drive shaft for actuating said agitator unit, means comprising a pair of levers for moving the agitator unit into raised and lowered positions, and a three wall housing constituting part of said unit and movable therewith, and a manually actuated clutch controlling drive between the main and the supplemental shafts.
